ATTACHMENT FOR STAPLING MACHINES

John Thomas Dalton, Durham, N. C., assignor to
 Golden Belt Manufacturing Company, Inc.,
 Durham, N. C., a corporation of New Jersey

Application December 31, 1938, Serial No. 248,710

12 Claims.

(Cl. 1-2)

This invention relates to wire stitching or stapling machines and more particularly to a feeding attachment for a wire stitcher or stapling machine.

- 5 In my copending application, Serial No. 234,916 filed October 14, 1938, I have disclosed and claimed a mechanism for attaching a tag to the string of a bag, such as a tobacco bag. The invention disclosed therein includes means for delivering the bags to the stitching machine and arranging the string on the anvil of the stitching machine and means for stitching tags to the string, the operation of the parts being coordinated with the operation of the stitcher head.
- 10 15 The present invention relates more specifically to the bag feeding mechanism. In the machine forming the subject matter of the present application, I employ the mechanism disclosed and claimed in the said copending application to feed tags to the anvil with a step by step movement coordinated with the operation of the stitching machine, or any other suitable means for so feeding the tags. In place of the bag feeding mechanism disclosed in said application, I employ an endless chain having brackets mounted thereon. These brackets form pockets which are adapted to receive the bags and convey them toward the anvil of the stitching machine with one of the bag strings arranged so that it can be fed to the 20 25 30 anvil of the stitching machine.

The invention further comprises guiding means for the bag strings together with a device for engaging a string and positioning it over the anvil prior to the stitching operation.

- 35 In the accompanying drawings, I have shown one embodiment of the invention. In this showing

Fig. 1 is a front view of a stitching machine showing the bag feeding means applied thereto;

- 40 Fig. 2 is a skeleton perspective view of the drive mechanism;

Fig. 3 is a detailed sectional view of apparatus for separating the two portions of a bag string prior to its delivery over the anvil of the stitching machine;

- 45 Fig. 4 is a detailed perspective view on an enlarged scale of a portion of the bag feeding mechanism and the associated bag string guiding mechanism;

- 50 Fig. 5 is a plan view of the same parts;

Fig. 6 is a perspective view of a hook which engages the bag string and carries it over the anvil together with the drive mechanism therefor;

- 55 Fig. 7 is a detailed perspective view of the stitcher head, anvil and associated parts, showing

the position of the bag, bag string and tag immediately prior to the descent of the stitcher head;

Fig. 8 is a skeleton perspective view of a portion of the drive mechanism and device for opening the bag string;

Fig. 9 is a side elevation, broken away, of a portion of the bag conveying mechanism, the anvil and stitcher head and the string handling mechanism showing the relative position of these parts; and

Fig. 10 is a plan view of the parts shown in Fig. 9 with the stitcher head removed.

The apparatus forming the subject matter of the present invention, in its broadest aspects, comprises a frame or bed A, a wire stitcher B, a bag feeding mechanism C and a tag feeding mechanism D.

The frame may be of any suitable construction for supporting the various parts and preferably consists of a table 1 and suitable legs 2, the bottom of the legs being broken away in Fig. 1 of the drawings.

The bag feeding mechanism is supported by suitable auxiliary frame or bracket 3 secured to the front of the main frame.

The wire stitching machine may be of any suitable construction, for instance, such as is shown in the patent to Maynard, No. 1,302,402, a detailed description thereof is believed to be unnecessary. As shown in Figs. 1 and 2, the wire stitching mechanism may comprise a suitable stitcher head 4, mounted on an arm 5, secured to the bed of the machine by bolts arranged in flanges 6 on the base of the wire stitcher. It may be driven by a motor 7, whose shaft carries a pinion 8 (see Fig. 2) meshing with a gear 9, mounted on the main shaft (not shown) of the wire stitching machine, which shaft extends through the horizontal portion of the arm 5.

As shown in Figs. 7 and 9, an anvil 10 is arranged beneath the stitcher head 4. The stitcher head carries a reel 11 upon which is mounted a coil of wire 12, and the wire is fed from this coil through a guide tube 13 into the stitcher head. A tag 14 is delivered to the anvil by suitable tag feeding mechanism having a step by step motion coordinated with the operation of the stitcher head to deliver a tag to the anvil between each two descents of the stitcher head. At the same time, a bag 15 is fed into position, whereby one of its strings 16 may be arranged over the anvil to stitch the tag to it.

The bag feeding mechanism (see Figs. 1, 2, 4 and 5) consists of a plurality of sprocket chains 17 passing over sprocket wheels 18 at the inlet

10

end of the bag feeding mechanism and sprocket wheels 19 at the outlet end of the bag feeding mechanism. Sprocket wheels 18 are carried by a shaft 20 and sprocket wheels 19 are likewise carried by a shaft 21. These shafts being mounted in suitable bearings carried by the auxiliary frame 3. The shaft 18 is driven from the main shaft of the wire stitching machine.

As shown in Figs. 4 and 9 of the drawings, certain of the links of the sprocket chain 17 are provided with extensions 22. A plurality of plates 23 are secured to the chains and these plates form the base or support of the bag holding means. As shown, the plates are provided with flanges 24 and suitable fastening members are arranged in aligned openings in these flanges and in the openings formed in the extensions 22 of the links of the sprocket chains. Curved arms 25 and 26 extend outwardly from the plates 23. A pair of such arms form a pocket for the reception of a plurality of bags 15 as shown in Figs. 4, 5 and 10. Arm 26 of each pair, engages the adjacent end of the arm 25 of the next pair as indicated at 27. The engagement of these arms not only adds to the rigidity of the structure, but also prevents the bags from being improperly placed on the chain.

Shaft 20 is driven from the main shaft through suitable drive mechanism shown in Fig. 2 of the drawings. As shown, the main shaft of the wire stitcher carries a sprocket wheel 28, over which passes a chain 29. The chain also passes over a sprocket wheel 30, mounted on a shaft 50 which shaft is arranged substantially on the level on the frame of the machine and extends forwardly. Shaft 50 is mounted in suitable bearings 51, carried by brackets 52 secured to the frame of the machine. The rear end of shaft 50 is provided with a hand wheel 53 to permit manual operation of the machine. The opposite end of shaft 50 is provided with a bevel gear 54 meshing with a bevel gear 55 on a shaft 56. The outer end of shaft 56 is provided with a sprocket wheel 57 and this sprocket wheel is aligned with a sprocket wheel 58 mounted on a main drive shaft 59. A sprocket chain 60 passes over the sprockets 57 and 58 to drive the main shaft from the shaft 56. Shaft 20 of the bag feeding mechanism is also driven from the shaft 56 by means of a worm 61 mounted on shaft 56 and worm gear 62 mounted on shaft 20.

From the above, it will be seen that bags placed in the pockets formed by the plates 23 and the arms 25 and 26 will be carried from the right in Fig. 1 past the stitcher head of the stitching machine to the other end of the bag feeding mechanism. A plurality of bags are placed in the pockets by an operator as the sprocket chain begins its upper flight and fed past the stitcher head and these bags fall out at the point 63 where the chain is about to begin its lower flight and where the arms 25 and 26 are spaced from each other by the passage of the chains around the sprocket wheels 19.

Suitable means are also provided for separating and straightening the bag strings as they feed toward the stitcher head. As shown in Figs. 4 and 9, the bags are arranged on their sides, and the lower set of strings 16 are adapted to be fed to the stitcher head with the upper set of strings depending in front of the bags. Worm shaft 64 is arranged across the front of the machine slightly spaced from the bag feeding chain (see Fig. 10) and this worm shaft is driven from the shaft 56 by a pair of sprocket

wheels 65 and 66 mounted on the two shafts and connected to each other by a sprocket chain 67. As the operator places a plurality of bags in one of the pockets on the chain, he separates the bag strings and arranges them in the spiral of the worm as shown in Figs. 4, 5, and 10 of the drawings. The strings remain thus separated as the bags are fed toward the stitcher head thereby permitting the bag string engaging mechanism to engage an individual bag string 10 loop and feed it to the stitcher head.

The bag string engaging mechanism is arranged adjacent the stitcher head and is provided with a reciprocating movement across the front of the machine to bring it into position to engage a bag string and to remove it from engagement with the bag string at the proper time. It is further provided with an oscillating movement to feed the bag string into a position over the anvil for the stitching operation.

As shown, the main drive shaft 59 is provided with a cam 68 having a cam groove adapted to receive a pair of rollers 69 carried by a reciprocating member 70. The reciprocating member 70 is adapted to reciprocate in suitable guides 71 on the frame of the machine. A curved arm 72 is pivoted to the end of the reciprocating member as at 73 and a horizontal arm 74 is attached to the free end of this arm. The end of the horizontal arm 74 is provided with a reduced portion forming a hook 75 adapted to engage a bag string 16. The reciprocation of member 70 works the arm 74 and hook 75 into position to engage the bag string. The hook 75 and arm 74 are also adapted to be oscillated to carry the bag string in a direction from the front toward the back of the machine over the anvil 10. This is accomplished by means of an oscillating shaft 76 which is carried by the reciprocating member 70. The shaft 76 carries an elongated gear 77 which meshes with a rack 78. The rack 78 reciprocates in suitable guides 79 carried by a plate or frame 80 which is supported from the frame of the machine by an arm 81. Rack 79 is reciprocated to oscillate the shaft 76 from a shaft 82 which is parallel to the main shaft and is driven from the main shaft. As shown (see Fig. 2) the main shaft is provided with a pinion 83 meshing with a pinion 84 on the shaft 82. Shaft 82 is provided with a cam 85 having a groove adapted to receive a roller 86. The roller 86 is carried by an arm 87 which is pivoted to the frame of the machine as at 88 and which is connected to the rack 78 by a link 89.

Oscillation of the shaft 76 causes the arm 74 and the hook 75 to be oscillated by means of a crank 100 connected on the end of the shaft 76 and connected to the curved arm 72 by a link 101. The link 101 is connected to the arm 72 at a point adjacent its pivot 73, whereby a wide oscillating movement is imparted to the arm 74 and hook 75 upon a slight oscillation of shaft 76. The forward end of the reciprocating member 70 is also provided with a vertical arm 102 which carries a horizontal arm 103 having a notch 104 in its outer end. The notched end 104 of the arm 103 is adapted to engage the edge of a tag 14 (as shown in Fig. 6) to move the tag and place it in proper position for the stitching operation.

The string at each side of the bag is in the form of a loop and the hook 75 is adapted to enter this loop. The apparatus is provided with means for opening the loop just as the hook is about to enter it to insure the entrance of the hook into the loop. A detailed view of this ap-

paratus is shown in Figure 3 of the drawings, the drive mechanism of the loop separating apparatus is shown in Figure 8 of the drawings and its position and relation with respect to the other parts of the apparatus is shown in Figures 1, 2, 9 and 10 of the drawings.

5 The separating member comprises a curved arm 110 which is pivotally mounted at 119 on toggle members 116 and 118 supported on the machine.

10 Main drive shaft 59 is provided with a beveled gear 112 on its outer end which meshes with a beveled gear 113 mounted on a shaft 114. (see Figure 8). The opposite end of shaft 114 is provided with a disk 115. An arm 116 is eccentrically connected to this disk as at 117. The arm 116 forms one arm of a toggle member, the other arm 118 being connected to the arm 116 by pin 119 and this pin also pivotally connects the toggle members to the string separating arm 110. The other end of arm 118 is pivoted in a bracket 120 carried by the frame of the machine. A spring 121 is connected to toggle arm 118 intermediate its ends and to the lower end of the string separating and lifting arm 110. The spring 121 holds the arm 110 in normal upright position. Pin 111 engages arm 110, and acts as a stop to prevent further movement of the arm in a clockwise direction by the spring 121. The upper end of arm 110 is provided with a downwardly extending notch 123.

15 In operation the eccentric mounting of the arm 116 on the disk 115 alternately opens and closes the toggle arms 116 and 118 and moves the connected end of those arms through a circle. On the upward movement the notch 123 is brought into position to engage the upper string of the loop 16 and separate the strings, as shown in Figure 3 of the drawings, to facilitate entrance of 20 the hook 75 into the loop. Spring 121 causes the arm 110 to exert a yielding pressure on the string. On the downward movement the arm 110 is moved away from the string and does not engage it.

25 Tags 14 are delivered to the anvil 10 of the stitching machine, the feed of the bags being coordinated with the operation of the stitcher so that a tag will be delivered to the anvil prior to each descent of the stitch ahead. These tags 30 may be fed by any suitable feeding mechanism such as that disclosed in my copending application referred to above. The tags are arranged in a tube 130 (see Figure 2) the inner diameter of which is substantially equal to the diameter of 35 the tags so that the tags are arranged therein in a column. A plate 131 is arranged on the top of this tube, the plate having an opening substantially equal in diameter to the diameter of the tube. The tags are fed through this opening from a hopper 132 which is oscillated on the plate 131. As shown in Figure 2, shaft 82 is provided with a pair of beveled gears 133 and 134 meshing with beveled gears 135 and 136, respectively, on vertical shafts 137 and 138. Shafts 137

40 and 138 carry disks 139 and 140 on their upper ends. An arm 141 is eccentrically connected to these disks and a second arm 142 is secured thereto. The arm 142 carries a collar 143 which surrounds a neck 144 on the bottom of the hopper 45 40. In operation the hopper is oscillated by the movement of arms 141 and 142 and a supply of tags arranged in the hopper are thus agitated and fed into the tube 130. The shaft 138 also carries a pair of cams 145 and 146 to impart motion to arms 147 and 148 by means of which

the apparatus for feeding a single tag from the bottom of the tube 130 (not shown) is actuated.

5 In the operation of the machine an attendant places a suitable number of the bags in the pockets formed by the plates 23 and the arm 25 and 26 at the right end of the machine in Figure 1. At the same time the individual strings which are on that side of the bags which rest on plate 23 are arranged in the grooves of worm 64, as shown in Figs. 3, 4, 5 and 10 of the drawings. 10 The upper flight of the bag feeding chains travels from the right to the left in Figure 1 of the drawings past the anvil 10 of the stitching machine. The feed is coordinated with the operation of the stitcher head to bring one bag in position for 15 arranging the string 16 over the anvil prior to each descent of the stitcher head. A tag 14 is fed to the stitcher head at the same time. As the bag approaches the anvil, the string separating member 110 engages the upper string of the 20 loop, as shown in Figs. 3 and 9 of the drawings, to separate the two strings of the loop. When the strings are separated the reciprocating member 25 70 travels across the machine toward the stitcher head and hook 75 enters the loop. At the end of this reciprocation of member 70 the arm 74 and hook 75 are oscillated by the oscillation of shaft 76 to bring the bag string over the anvil, as shown in Figure 7 of the drawings. Just prior to the descent of the stitcher head, the reciprocating member 70 travels in a reverse direction so that hook 75 is withdrawn and is out of the way when the stitcher head descends. Upon the descent of stitcher head the tag 14 is stitched to the string 16 of the bag. The bags continue to travel toward the left, as in Figure 1 of the drawings, and as the chain passes over the sprocket 19 the arms 25 and 26 forming the pocket are slightly separated and the bags, with the tags attached thereto, fall out of the pocket by gravity.

30 I claim:

1. In combination with a wire stitching machine, an endless belt arranged in front of the anvil of the stitching machine to feed bags of the string closure type thereto with the strings disposed on the side of the belt toward the anvil, means for separating and positioning the strings of the individual bags, and means for feeding a bag string to the anvil.

40 45 50 55 2. In combination with a wire stitching machine, an endless belt arranged in front of the anvil of the stitching machine, pockets formed on the belt for the reception of bags of the string closure type with the strings of the bags disposed on the side of the belt toward the anvil, means for separating and positioning the strings of the individual bags, and means for feeding a bag string to the anvil.

3. In combination with a wire stitching machine, an endless belt arranged in front of the anvil of the stitching machine, said belt including a plurality of chains, plates carried by said chains, curved plates mounted on the first mentioned plates and forming pockets for the reception of bags of the string closure type with the strings of the bags in the pockets arranged on the side of the belt toward the anvil, means for separating and positioning the strings of the individual bags, and means for feeding a bag string to the anvil.

60 65 70 75 4. In combination with a wire stitching machine, an endless belt arranged in front of the anvil of the stitching machine to feed bags of the string closure type thereto, and a worm shaft arranged adjacent the belt, the strings of the bags

- being adapted to be arranged in the groove of said shaft.
5. In combination with a wire stitching machine, an endless belt arranged in front of the anvil of the stitching machine to feed bags of the string closure type thereto, pockets formed on the belt for the reception of the bags, and a worm shaft arranged adjacent the belt to receive the strings of the bags.
10. 6. In combination with a wire stitching machine, means for feeding bags of the string closure type to the anvil of the stitching machine, means for separating the strings of individual bags and positioning them in a horizontal plane, and means for separating the two strings of a loop.
7. In combination with a wire stitching machine, an endless belt arranged in front of the anvil of the stitching machine to feed bags of the string closure type thereto with the strings 20 of the bags arranged on the side of the belt toward the anvil, means for separating the strings of individual bags and positioning them in a horizontal plane, and means for separating the strings of a loop.
25. 8. In combination with a wire stitching machine, an endless belt arranged in front of the anvil of the stitching machine to feed bags of the string closure type thereto, a worm positioned adjacent the belt and adapted to receive the string 30 loops of the bag, and means for separating the two strings of a loop.
9. In combination with a wire stitching machine, an endless belt arranged in front of the

anvil of the stitching machine to feed bags of the string closure type thereto, means for separating and positioning the strings of the bags, and an oscillating hook to deliver the bag string over the anvil of the stitching machine.

10. In combination with a wire stitching machine, an endless belt arranged in front of the anvil of the stitching machine to feed bags of the string closure type thereto, a worm shaft arranged adjacent the belt and adapted to receive 10 the strings of the bag, and an oscillating hook adapted to deliver a bag string over the anvil of the stitching machine.

11. In combination with a wire stitching machine, an endless belt arranged in front of the 15 anvil of the stitching machine to feed bags of the string closure type thereto, means for separating and positioning the strings of the bag, a reciprocating member arranged adjacent the anvil of the stitching machine, and an oscillating 20 hook carried by said member and adapted to engage the bag string.

12. In combination with a wire stitching machine, an endless belt arranged in front of the 25 anvil of the stitching machine to feed bags of the string closure type thereto, means for separating and positioning the strings of the bag, a reciprocating member arranged adjacent the anvil of the stitching machine, an oscillating shaft 30 mounted on said reciprocating member, and a hook pivotally mounted on the reciprocating member and connected to said shaft.

JOHN THOMAS DALTON.
